TRUSS

Edward P. Riess, Sheboygan, Wis.

Application November 18, 1936, Serial No. 111,497

2 Claims. (Cl. 128—95)

This invention appertains to new and useful improvements in trusses such as are worn by persons having hernias or ruptures of the reducible type.

5 The principal object of the present invention is to provide a truss which will remain in place over the hernia or rupture and which will have a tendency to cause natural healing of the tissue rather than enlargement or a tendency not to 10 allow healing as occurs with the use of conventional types of trusses.

Another important object of the invention is to provide a truss wherein the pad has a contact plate constructed in such a manner as to cause 15 contraction of the abdominal tissues so as to support and promote healing over the hernia or rupture.

These and various other important objects and 20 advantages of the invention will become apparent to the reader of the following specification.

In the drawings:—

Fig. 1 represents a front elevational view of a double type of truss.

Fig. 2 is a front elevational view of one of the 25 truss units with its belt attaching plate.

Fig. 3 is an inside elevational view of the structure shown in Fig. 2.

Fig. 4 is a top plan view of the truss unit shown in Fig. 2.

30 Fig. 5 is a vertical sectional view through the truss unit.

Fig. 6 is a vertical sectional view on line 6—6 of Fig. 5.

Referring to the drawings wherein like numerals 35 designate like parts, it can be seen in Fig. 1, that numeral 5 represents the body of the patient and numeral 6 the waist encircling belt. Each of the truss units is generally referred to by numeral 7. Each of these units consists of an 40 ovate-shaped body 8, the lower end of the body being of sharper angular constriction than the upper portion. The inner side of this body 8 is hollowed out to provide a pocket 9 for receiving the pad 10. The inner side of the pad 10 is 45 hollowed out to provide the pocket 11 for the reception of the cushion insert 12.

It is to be understood that the body 8 is of a substantially stiff composition such as rubber or some other substance having only slight flexibility while the body 10 is of more resilient substance and preferably rubber. The insert 12 is of cushion material, preferably soft rubber and the wall portion *a* of the body 10 overlying the cushion insert 12 is quite thin. The entire body contact side of the body 10 is of concave formation and is provided with crossed ribs 13 to permit adherence to the human body.

Obviously the concaved surface of the body 10 has a tendency to constrict the rupture or hernia opening, pulling the wall of the abdomen over the protruding intestine.

A pair of nuts 14 are embedded in the upper 5 portion of the body 10 while a plate 15 is embedded in the lower portion of the body 10 and has a threaded opening therein for receiving the bolt 16. A pair of bolts 17—18 extends through the front wall of the body 8 and into the nuts 10 14, while another bolt 19 extends through the upper portion of the body 8 to engage into the nut 20 which is embedded in the body 10.

The belt attaching plate 21 has an opening 15 therein through which the bolt 17 is disposed, and adjacent thereto, the arcuate slot 22 through which the bolt 19 extends. Obviously, the unit 20 is interchangeable to be used on the right or left side of the abdomen by simply reversing the position of the plate 21. The ends of the plate 21 20 are provided with slots 23 to accommodate the belt 6 and the bolts 17 are sufficiently long to be engageable through openings in the belt 6. The crotch straps 24 which extend from the rear portion of the belt 6 have openings in their forward 25 ends for receiving the lower bolts 16 of a pair of units as shown in Fig. 1.

While the foregoing specification sets forth the invention in specific terms, it is to be understood that numerous changes in the shape, size and 30 materials may be resorted to without departing from the spirit and scope of the invention as claimed hereinafter.

Having described the invention, what is claimed as new is:—

1. A truss pad comprising a body of substantially stiff material having a pocket on the human body side thereof, a resilient body disposed in the said pocket and having corrugations on the human body engaging side thereof, the opposite side of the said resilient body being provided with a pocket, and a cushion insert in the last-mentioned pocket, the wall of the resilient body defined by the bottom of the pocket and the human body engaging side of the resilient body 40 being substantially thin.

2. A truss comprising waist encircling means, a pad structure including a substantially stiff body having a pocket on the human body opposing side thereof, a flexible body disposed in the 50 pocket, a nut member embedded in the said flexible body, a threaded member disposed through the substantially stiff body and into the nut, and means on the waist encircling member engageable with the said threaded member to hold the 55 said pad substantially fixed on the waist encircling member.

EDWARD P. RIESS.
